UNITED STATES PATENT OFFICE.

WILLIAM L. SÜTTERLIN, OF TRENTON, NEW JERSEY.

OAR-LOCK.

SPECIFICATION forming part of Letters Patent No. 680,289, dated August 13, 1901.

Application filed December 15, 1900. Serial No. 40,048. (No model.)

To all whom it may concern:

Be it known that I, WILLIAM L. SÜTTERLIN, a citizen of the United States, residing at Trenton, in the county of Mercer and State of New Jersey, have invented new and useful Improvements in Oar-Locks, of which the following is a specification.

This invention relates to new and useful improvements in oar-locks; and its primary object is to provide a device of simple and durable construction which may be readily secured to gunwales of a boat and which is provided with means whereby the same is prevented from being withdrawn therefrom except as desired.

Another object is to provide means of novel construction, whereby the oars will be held securely within the oar-lock.

With these and other objects in view the invention consists in providing a stem which is provided at its upper end with a yoke of ordinary construction. To each end of this yoke is pivoted a dog having an inwardly-extending portion and a weighted outer portion, said outer portion being adapted to hold the inner extensions normally in a substantially horizontal position. Dogs are also pivoted to the stem at the lower end thereof and are normally held in a horizontal position, but may be, if desired, swung vertically into recesses provided therefor, thereby permitting the oar-lock to be readily removed from the gunwale in which it is mounted.

The invention also consists in the further novel construction and combination of parts hereinafter more fully described and claimed, and illustrated in the accompanying drawings, showing the preferred form of my invention, and in which—

Figure 1 is a side elevation of the device in position upon the gunwale of a boat. Fig. 2 is a central vertical section through the device, showing the stem in elevation. Fig. 3 is an end view of a modified form of oar-lock; and Figs. 4 and 5 are detail views of a portion of the stem of a modified form of oar-lock and of a receiving-plate therefor, respectively.

Referring to the figures by numerals of reference, 1 is a stem provided at its upper end with a yoke 2, having a shoulder 3, which is adapted to bear upon the gunwale of the boat. To each end of this yoke 2 is pivoted

a dog 4, said dog comprising a weighted portion 5, which is located at the outer side of the yoke and an inner extension 6, which is held normally in a substantially horizontal position by said weighted portion. These inner extensions are of such length as to prevent the upward movement of an oar after the same has once been placed within the yoke. These dogs 4 are, as shown in Fig. 2, preferably pivoted within recesses formed at the ends of the yoke. The stem 1 is recessed on opposite sides at points adjacent to its lower end, as at 7, and within each recess is pivoted a dog 8. The lower walls of the recesses are adapted to support these dogs normally in horizontal position and the dogs are so mounted as to extend in opposite directions from the shank. The recesses 7 are large enough to permit the dogs to swing thereinto when raised.

It will be readily seen that when it is desired to secure the oar-lock within a gunwale the stem 1 is inserted into the proper aperture, forcing the dogs 8 up into their recesses 7. As soon as these recesses pass below the opening within the gunwale the dogs 8 will fall outward by force of gravity and will prevent the withdrawal of the stem until they have been swung upward into their respective recesses.

When it is desired to place an oar within the yoke 2, the same is placed upon the extensions 6 of the dogs 4, forcing the same downward until the ends thereof are passed by the oar. The weighted ends 5 of the dogs will then swing the extensions 6 upward to their normal positions. The upward movement of the oar will be prevented until said extensions are pressed downward.

While I prefer the construction hereinbefore described, I do not limit myself thereto, for, if desired, the dogs 4 may be pivoted within slots formed within the ends of the yoke 2, and the dogs 8 may be similarly mounted within a slot 9 in the stem 1. This construction I have illustrated in Fig. 3.

In the foregoing description I have embodied the preferred form of my invention; but I do not limit myself thereto, as I am aware that modifications may be made therein without departing from the spirit or sacrificing the advantages thereof, and I therefore

reserve the right to make all such changes as may fairly fall within the scope of the following claims. Among these modifications is the one which I have illustrated in Figs. 4 and 5.

- 5 With this construction of oar-lock the pivoted dogs 8 in the stem are dispensed with and lugs 10 employed in lieu thereof. These lugs are adapted to be in alinement with the arms of the yoke, and plate 11 is adapted to be secured to the gunwale and to receive the stem. Recesses 12 are suitably located within the sides of this plate, so as to permit the lugs 10 to pass through the aperture.

Having thus fully described my invention, 15 what I claim as new, and desire to secure by Letters Patent, is—

1. In an oar-lock, the combination with a stem; of a yoke thereto; a dog pivoted to each end of the yoke and each dog having an inwardly-extending portion and an outer weighted portion.
2. In an oar-lock, the combination with a stem; of a yoke thereto having recesses at its ends; a dog pivoted within each recess; an

inwardly-extending portion to the dog; and a weighted outer end to the dog adapted to hold the inner extension normally in a horizontal position.

3. In an oar-lock, the combination with a yoke; of a stem thereto having recesses therein; and a dog pivoted within each recess, said dogs being supported normally in a horizontal position by the end walls of the recesses.

4. In an oar-lock, the combination with a yoke; of dogs pivoted to the ends thereof; inwardly-extending portions to the dogs; outer weighted portions thereto; a stem; dogs pivoted within recesses of the stem and adapted to normally extend laterally from said stem in opposite directions and to be retracted into the recesses.

In testimony whereof I affix my signature in presence of two witnesses.

WILLIAM L. SÜTTERLIN.
